A. J. O'Donnell, Attorney

UNITED STATES PATENT OFFICE.

EDWARD F. McCOOL, OF VICTOR, COLORADO.

LATCH FOR GRINDING-MILLS.

1,321,540.

Specification of Letters Patent. Patented Nov. 11, 1919.

Application filed June 4, 1918. Serial No. 238,093.

To all whom it may concern:

Be it known that I, EDWARD F. McCool, a citizen of the United States, residing at Victor, county of Teller, and State of Colorado, have invented certain new and useful Improvements in Latches for Grinding-Mills; and I do declare the following to be a full, clear, and exact description of the invention, such as will enable others skilled 10 in the art to which it appertains to make and use the same, reference being had to the accompanying drawings, and to the characters of reference marked thereon, which form a part of this specification.

15 My invention relates generally speaking to improvements in grinding mills, but more specifically in means for locking a hollow grinding head or housing member of the structure in place, this housing member being hingedly connected with the frame work 20 of the machine and adapted to swing outwardly whenever it may be necessary to gain access to the grinding structure within the hollow head or housing member.

25 My object is to provide a device adapted to securely lock the housing member in place upon the frame, the lock being operated by simply pushing the head into position, the device automatically assuming the interlocking 30 relation under the force of the movement of the head. My further object is to provide a device of this character of such construction that the hollow head or housing member may be quickly released and thrown to 35 the open position.

An additional object of my improvement is to provide a locking device which shall be exceedingly simple and therefore, economical in construction.

40 Having briefly outlined my improvement I will proceed to describe the same in detail, reference being made to the accompanying drawing in which is illustrated an embodiment thereof.

45 In this drawing:

Figure 1 is a top plan view of the portion of an ore grinder with which my improved lock is adapted for use, the lock being shown in place with the housing member indicated 50 by full lines in the open position and by dotted lines in the closed position.

Fig. 2 is an elevation of the lock shown on a much larger scale and looking in the direction of arrows 2, Fig. 1.

Fig. 3 is a section taken on the line 3—3, 55

Fig. 2.

Fig. 4 is a section taken on the line 4—4, 60
Fig. 2.

The same reference characters indicate the same parts in all the views. 65

Let the numeral 5 designate a suitable relatively stationary frame constituting a part of a grinding mill. This construction includes a hollow shaft 6 and a shaft 7 eccentrically mounted therein. In this construction the two shafts rotate at different speeds, the shaft 6, rotating on its individual axis and having orbital travel by virtue of its eccentric mounted in the hollow shaft during the rotation of the latter. A grinding member 8 is secured to one extremity of the shaft 7 and coöperates with a second grinding member 9 (see dotted lines in Fig. 1), the latter being mounted within a hollow head or housing 10 which is hingedly connected with the frame, as shown at 12. When the hollow head or housing member 10 is in the closed position the two grinding members 8 and 9 coöperate. 70

Upon the housing 10 is mounted a lock 80 13 consisting of a leverlike device 14 which is pivotally connected, as shown at 15 with a lug 16 projecting from one side of the housing 10. The device 14 extends in both directions from the pivot 15, that is both 85 toward the right and toward the left referring to Figs. 1, 2 and 3. The device 14 is hollowed out to receive the lug 16 of the housing, so that when the device is in the locked position the said lug would be practically concealed. The right hand portion 90 17 of the device 14 extends sufficiently beyond the pivot to give the necessary leverage for unlocking the housing by pressing the said part inwardly to the position shown by dotted lines in Fig. 3, the device being normally held in the full line position by a torsionally acting spring 18 which is coiled around the pivot pin 14, one extremity 19

engaging the housing, while the opposite extremity 20 engages the part 17 considerably to the right of the pivot pin. The left hand portion of the device 14 extends beyond the lug 16 and is equipped with an antifrictional roller 21 which as the housing is moved from 100 the full line position to the dotted line position in Fig. 1, first engages the curved face 22 of a lateral projection 23 with which the 105

frame work of the structure is provided. Under the influence of the momentum of the head, the roller 21 moves past this projection and into engagement with the protruding extremity of a stud 24 with which the projection 23 is provided. In order to prevent the roller 21 from moving farther inwardly than desired, I equip the device 14 with a set bolt 25 which is threaded into the said device and adapted to engage the lug 16, when the roller 21 is in engagement with the exposed end of the screw stud 24. The set bolt 25 when properly adjusted is held in such position by a lock nut 26. The screw stud 24 is adjustable in the projection 23, its extremity adjacent the curved face 22 having a nick adapted to receive a small screw driver. The stud is devoid of a head thus giving it a range of adjustment equal to its full length, in order to provide for possible wear. Should one screw stud wear out another may be substituted. A lock nut 27 mounted on the protruding portion of the screw stud is employed to lock it in the desired position of adjustment.

From the foregoing description, the use and operation of my improved locking device will be readily understood. Assuming that the device is mounted upon the housing 10, as shown in Fig. 1, if the head is open, as shown in full lines, it will only be necessary to swing the head into the closed position as outlined in dotted lines, in order to cause the device 14 to interlock with the screw stud 24, the set bolt 25 having first been properly adjusted with this in view. Again, when it is desired to open the housing, it is only necessary to press upon the part 17 of the device or move the latter into the dotted line position in Fig. 3, in which event the roller 21 will be disengaged from the screw stud 24, when the housing may be swung to the full line position in Fig. 1, thus exposing the grinding members 8 and 9 and making it practicable to remove or repair their grinding faces. It is evident that it is important to securely lock the housing 10 in place in order to prevent the escape of the dust or pulverized material during the operation of the machine, the material to be treated being fed into a chute or mouth 28 with which the housing member 10 is provided, this mouth being located at the top of the said member and so arranged as to guide the material into position to be acted on by the grinding disks 8 and 9.

I claim—

1. The combination of a frame, a housing hingedly connected with the frame, locking means comprising a device pivoted intermediate its extremities to the housing, a spring carried by the pivot and acting on the device on one side of the pivot to throw the part on the opposite side toward the housing, the said part carrying a roller, means

carried by the frame and coöperating with the roller for locking purposes, and adjustable means carried by the said device for limiting the inward movement of its roller extremity.

2. The combination of a frame, a housing hingedly connected with the frame, locking means comprising a leverlike device pivoted intermediate its extremities to the housing, a spring acting on the device on one side of the pivot to throw the part on the opposite side toward the frame, the said device carrying a roller at one extremity, adjustable means carried by the frame and coöperating with the roller for locking purposes, and adjustable means carried by the said device for limiting the movement of its roller carrying extremity.

3. The combination with a frame, of a housing hingedly connected therewith and having an exterior lug, a leverlike device pivoted intermediate its extremities on the housing lug, a spring acting on one arm of the device to throw the other arm toward the frame which it is adapted to engage in locking relation, and means mounted on the device and adapted to limit its movement under the influence of the spring.

4. The combination with a frame, of a housing hinged thereto, a leverlike device pivoted intermediate its extremities to the housing, a spring acting on one arm to throw the other arm of the device toward the frame, the last named arm carrying an antifrictional roller member, the frame having a curved projection coöperating with said member to guide the device into locking relation with the frame.

5. The combination of a frame, a hinged housing having a lateral projection, a leverlike device pivoted intermediate its extremities on said projection, a spring acting on one arm of the device to throw the other arm toward the frame, the last named arm carrying a roller, a stud mounted in the frame and engaging the roller in locking relation, and a set bolt threaded in the device and engaging the housing lug to limit the movement of the device under the influence of the spring.

6. The combination of a frame, a hinged housing having a lug extending therefrom, a leverlike device pivoted intermediate its extremities on said lug, a torsionally acting spring mounted on the said pivot and acting on one arm of the device to throw the other arm toward the frame, the last named arm carrying a roller, a stud threaded in the frame and adjustable to compensate for wear, one extremity of said lug being arranged to tangentially engage the roller for locking purposes, and a set bolt threaded in the device and bearing against the housing lug to limit the movement of the roller extremity of the device.

7. The combination with a frame of a housing hinged thereto, a lever-like device pivoted intermediate its extremities to the housing, a spring acting on one arm to throw the other arm of the device toward the frame, the last named arm carrying engaging means, the frame having a curved projection coöperating with said engaging means to guide the device into locking engagement with the frame, and an adjustable element on said projection to coöperate with said roller for locking purposes.

In testimony whereof I affix my signature.

EDWARD F. McCOOL.
